CLAIM

We claim the ornamental design for a rail with end cap for an architectural covering, as shown and described.

DESCRIPTION

FIG. 1 is an isometric view of a rail with end cap for an architectural covering in accordance with the present design.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view thereof; and,

FIG. 7 is a bottom plan view thereof.

The break lines symbolize breaks in the length of the article in which the claimed design is embodied. The appearance of any portion of the article between the break lines forms no part of the claimed design.
